UNITED STATES PATENT OFFICE.

JOHN PARAMOR, OF WATFORD, ENGLAND, ASSIGNOR OF ONE-HALF TO THE WATFORD ENGINEERING WORKS, LIMITED, OF WATFORD, HERTS COUNTY, ENGLAND.

MACHINE FOR STRAINING PAPER PULP.

Application filed September 1, 1921. Serial No. 497,787.

(GRANTED UNDER THE PROVISIONS OF THE ACT OF MARCH 3, 1921, 41 STAT. L., 1313.)

To all whom it may concern:

Be it known that I, JOHN PARAMOR, a subject of the King of Great Britain and Ireland, residing at 6 Kingsfield Road, Watford, in the county of Herts, England, have invented new and useful Improvements in Machines for Straining Paper Pulp (for which I have filed application in Great Britain on Nov. 13, 1918, Patent No. 134923), of which the following is a specification.

This invention relates to paper-pulp straining machines of the rotating drum type, the pulp under treatment flowing either inwardly or outwardly. In straining machines of this type, it is usual to subject the drum to vibration in order to facilitate the passage of the pulp through the straining medium. My present invention consists in improved means for imparting to the drum a vibratory motion of a positive character, the extent of which is moreover capable of variation according to the nature of the pulp under treatment.

In the accompanying drawings are illustrated means for carrying my invention into effect; Fig. 1 being a side elevation of an outward-flow strainer of the Wandel type, Fig. 2 an end elevation and Fig. 3 a plan view thereof. Fig. 4 is a side elevation of an inward flow strainer, Fig. 5 an elevation, Fig. 6 a plan view and Fig. 7 a transverse section thereof. Figs. 8, 9, 10 and 11, illustrate certain details of construction herein-after more particularly referred to.

Referring to Figs. 1, 2 and 3, I mount the drum A on cradle or jog-arms B, one extremity of each of the said arms being supported on a floating fulcrum C furnished by a rigid link D, whilst the other extremity thereof is in direct engagement with a compound eccentric formed on or attached to a revolving shaft F. Between the jog-arm B and the eccentric E is fitted a second eccentric G, capable of being rotated about the first one and of being secured relatively thereto in any desired angular position. By changing the angular position of the adjustable eccentric G, upon the eccentrically turned shaft E, the extent of the vibratory motion imparted to the jog-arm B, is varied; the throw of the one eccentric being added to or deducted from that of the other.

The strainer is provided with a spray-pipe H, supported by the column I, an inlet J, for the stuff to be strained, and a knot-catcher L, furnished with suitable brackets for carrying same. The shaft F is coupled to the eccentrically turned extension thereof, E, by a coupling M; the eccentric shaft 55 being mounted in plummer blocks.

For washing the slits whilst passing the spray-pipe H, the drum A revolves slowly and may be rotated in any convenient manner; but I prefer to effect its rotation by 65 means of a pad O, formed of suitable material, such as "Ferodo," fixed upon the jog-arm B; the said pad acting upon the treads P attached to the respective drum-ends Q. The drum-ends rest upon the jog-arms B in the usual manner, but we make the diameter of the treads P substantially greater than that of the drum-ends Q; in order that the turning moment of the "Ferodo" pads O may be substantially in 70 excess of the resistance of the drum-ends Q revolving in the jog-arms B. The Ferodo pad O is placed in the jog-arm near the driving shaft F, and, owing to the motion of the jog-arm B, there occurs, between the 75 Ferodo pad O and the tread P, a frictional grip sufficient to revolve the drum.

By the use of an eccentric motion for imparting a vibratory movement to the drum A, it is possible to use a deeper vat R; as the 85 drum moves not only vertically but laterally, and is hereby rendered much more effective.

In Figs. 4, 5, 6 and 7, which illustrate the application of my invention to an inward-flow strainer, the drum A is submerged in 90 the vat R, the stuff entering by the inlet S. The application of the eccentric motion, the jog-arms and their suspending links, is as already explained with reference to the outward flow strainer; but the jog-arms B, are 95 provided with straps T which pass over the drum-ends Q in order to prevent the drum floating in the vat R. The stuff passing through the slits in the drum A pass out of the latter, by way of the drum-ends Q, into 100 the trough U, and escape thence through the regulating valve V.

The vat R is also fitted with a scum-trough W to carry away the floating refuse and the like. The drum may be rotated in 105 any convenient manner; but in this instance,

I prefer to operate same by means of the ratchet wheel X, fitted with a pawl Y. Motion is imparted to the pawl Y by means of gearing enclosed in the gear-box Z, eccentric A¹, connecting-rod B¹ and arm C¹ to which the pawl Y is attached. The said gearing is driven from the main shaft F by any suitable means. D¹ is a drip-tray; and the joints E¹, for sealing the drum A 10 in the vat R, are of the usual character. The bottom of the vat R is provided with suitable out-lets F¹ for cleaning-out purposes. The top of the gear-box Z is provided with a flexible apron G¹ attached to the connecting-rod B¹, thereby forming a water-tight joint on the mouth-piece of the said gear-box.

Figs. 8, 9, 10 and 11, show in greater detail the construction and arrangement of the 20 duplex eccentric E, G; Fig. 8 being a side view of the shaft F and eccentric E, and Fig. 9 an end view thereof; whilst Figs. 10 and 11 are side and end views of the eccentric G. The portion E of the shaft F is 25 turned eccentric, and thereabout is mounted the eccentric and split sleeve G, formed with lugs traversed by a screw-bolt. By rotating the eccentric sleeve G upon the eccentric portion E of the shaft F and then tightening

the pinching bolt, the former can be set in any angular position upon the latter, so that the eccentricity of the one is either added to or subtracted from that of the latter.

I claim:—

1. In a paper-pulp strainer of the rotary drum type, the combination, with a trunnion-ended straining drum, of a cradle-arm in direct connection with an eccentric at one end, suspended or supported by means of a rigid link at its opposite end, and formed 40 at an intermediate point with a bearing in which the drum-trunnion is carried, substantially as and for the purpose set forth.

2. In a pulp strainer of the rotary drum type, a straining drum, a cradle arm supporting said drum, a driven shaft and eccentric for oscillating said cradle arm, and means located between said eccentric and cradle arm for varying the movement of said cradle arm.

3. In a pulp strainer of the rotary drum type, a straining drum, a cradle arm for supporting said drum, a pivotal support for one end of said cradle arm, and a variable throw eccentric for oscillating the opposite 55 end of said cradle arm.

JOHN PARAMOR.
